UNITED STATES PATENT OFFICE.

THOMAS J. DAVIS, OF DUQUESNE, AND JOHN W. FORSYTHE, OF WILKINSBURG, PENNSYLVANIA.

IGNITER CAR FOR SINTERING APPARATUS.

Application filed September 23, 1922. Serial No. 590,093.

To all whom it may concern:

Be it known that we, THOMAS J. DAVIS and JOHN W. FORSYTHE, citizens of the United States, and residents of Duquesne and Wilkinsburg, respectively, in the county of Allegheny and State of Pennsylvania, have invented certain new and useful Improvements in Igniter Cars for Sintering Apparatus, of which the following is a specification.

This invention relates to sintering apparatus and more particularly to igniter cars for initially igniting the materials to be sintered, and has for one of its objects the provision of an igniter car having a stationary body portion. That is a body portion that is not movable vertically relative to the sintering pan.

Another object is to provide an improved igniter car that is composed of fewer parts and is, therefore, more durable than those heretofore used.

A still further object is to provide an igniter car having the novel combination, construction and design of parts described in the following specification and illustrated in the accompanying drawings.

In the drawings Figure 1 is a side elevation of the improved igniter car.

Figure 2 is an end elevation thereof.

Figure 3 is a top plan view of the car.

Figure 4 is a longitudinal sectional elevation of the car, on the line IV-IV of Figure 3 showing it in position over a sintering pan.

Figure 5 is a cross sectional elevation on the line V-V of Figure 3.

Referring more particularly to the drawings, the numeral 2 designates a sintering pan of ordinary and well known construction, having a series of grates 3 therein for supporting the ore, flue dust, or the like to be sintered, which is designated by the numeral 4.

The improved igniter car to which this invention pertains comprises a rectangular rigid body frame 5 of box girder construction, having flanged wheels 6 mounted on axles 7 journaled in bearings 8.

The axles 7 at the rear end of the machine are provided with gears 9 which mesh with gears 10 on countershafts 11 journaled in bearings 12 on the frame 5, and the gears 10 are in mesh with spur or pinion gears 14 on a drive shaft 15 journaled in bearings

16. The drive shaft 15 receives its power from an electric motor 17 mounted on a bracket support 18 projecting beyond the rear end of the frame 5. The motor 17 is operatively connected to the shaft by gears 19 and 20.

The armature shaft of the motor 17 is provided with a brake drum 21 on which is mounted a brake band 22, which is connected to brake operating shaft 23 by levers 24. The shaft 23 is adapted to be rocked by a foot pedal 25.

The motor 17 receives its operating current from overhead conductors 26 through trolley 27, and is controlled by a controller 28 of any well known design.

The wheels 6 of the igniter are adapted to travel on rails 29 arranged parallel with the longitudinal axis of the sintering pan, and the lower edge of the frame 5 is in such close proximity to the sintering pan that such edge will engage the upper surface of the material being sintered. Wear plates 30 are removably secured to the bottom face of the frame 5 so as to take the wear caused by the igniter car passing over the material being sintered, and may be readily replaced as the frame becomes worn.

The side members of the frame 5 are provided with a longitudinal shelf 31 on which cross beams 32 are supported. The cross beams 32 are secured in position by bolts 33 and serve to brace and tie the frame together. Also they serve as burner plate supports.

The burner plates are divided into three groups, designated by the numerals 34, 34^a and 35. The plates 34 and 34^a are plain plates provided with apertures 36 for the admission of air, while the plates 35 are provided with air inlet apertures 37 and an enlarged burner receiving aperture 38, in which is mounted a gaseous fuel burner 39.

The burner plates 34 and 35 are provided along one side edge with a flange 40 adjacent the upper face of the plate, and along the other side edge with upper and lower flanges 41 and 42. The flange 42 is substantially the same width as the flanges of the cross beams 32 for a purpose to be described.

The burner plates 34^a are provided with the flanges 41 and 42, but are not provided with flange 40. The plates 34^a are end

plates and have their one side edge resting or supported on a rib or shelf 44 formed on the end beams of the frame 5.

The burner plates 34^a, as stated above, 5 are end plates and are arranged between the end beams of the frame 5 and the first cross beams 32. As thus arranged they have their one side edge supported on the rib 44 and their other side edge supported by the 10 flanges 41 and 42, the flange 41 resting on the upper face of the bottom flange of the beam 32, and their lower flange 42 projecting across the entire lower face of the bottom flange of the beam 32.

15 The burner plates 34 and 35 are arranged in alternate transverse rows across the device between the beams 32. The plates 34 and 35 are removably supported on the beams 32 by the flanges 40, 41 and 42. That 20 is, the flanges 40 of the plates rest on the upper face of the lower flange of one beam, while the flange 41 rests on the upper face of the lower flange of the next adjacent beam, and the flange 42 projects under the 25 complete lower face of the flange on the last named beam, thus protecting such flange from the intense heat generated by the burners.

The burners 39 have fuel pipes 45 connecting their upper ends with manifold pipes 46, which in turn are connected to a fuel supply pipe 47.

The fuel supply pipe 47 has a flexible extension 48 on its outer end, to which is secured a quick detachable coupling member 49 adapted to be coupled to the fuel supply main 50.

In the operation of the above described igniter, the body portion is not moved relative to the wheels as is necessary in most igniters heretofore used. The igniter is so constructed that it is spaced only slightly above the sintering pan, and in order to seal the space between the igniter and pan it is only necessary to slightly heap or overfill the pan, so that the igniter will be compelled to plow through the material in its movement over the pan, thus automatically forming a seal. Also during the operation if any of 45 the burners become broken or clogged they 50 may readily be removed without dismantling the apparatus.

The provision of the air inlet apertures in all the plates 34, 34^a and 35 permits an 55 abundance of air to support combustion of the material being sintered. It also serves to compel a complete combustion of the gaseous fuel from the burners.

While we have shown only the preferred 60 embodiment of our invention various modifications may be made within the scope of the appended claims.

We claim:

1. The combination with a sintering pan 65 adapted to support a quantity of material to

be sintered, of an igniter comprising a rigid main frame, wheels on said frame, said frame and said wheels having a fixed vertical position relative to each other, burners 70 removably mounted on said frame, and means mounted on said main frame for propelling said igniter.

2. The combination with a sintering pan 75 adapted to support a quantity of material to be sintered, of an igniter comprising a wheeled main frame, burners removably mounted on said frame, and means for supplying fuel to said burners, all parts of said igniter having a fixed vertical relation to 80 said sintering pan.

3. The combination with a sintering pan 85 adapted to support a quantity of material to be sintered, of an igniter comprising a main frame, wheels on said frame, said wheels being fixedly positioned on said main frame so that the lower edge of said main frame will be in close proximity to the upper face of said pan, a plurality of cross beams extending between the sides of said main frame, and burner plates removably mounted 90 between said cross beams and supported on the lower flanges thereof.

4. The combination with a sintering pan 95 adapted to support a quantity of material to be sintered, and track rails parallel with the sides of said pan, of an igniter comprising a rectangular main frame, wheels on said frame adapted to travel on said track, means carried by said frame for propelling said igniter, and burners removably mounted on 100 said frame, all parts of said igniter being so connected as to have a fixed vertical relation to said sintering pan.

5. The combination with a sintering pan 105 adapted to support a quantity of material to be sintered, and track rails parallel with the sides of said pan, of an igniter comprising a rectangular main frame, wheels on said frame adapted to travel on said tracks, a plurality of cross beams extending between the sides of said main frame, and burner plates removably mounted between said cross beams and supported on the lower flanges thereof, said plates having flanges 110 thereon adapted to underlie the lower flanges of said cross beams so as to protect them from the intense heat generated in said igniter.

6. In an igniter car comprising a rectangular wheeled main frame, and a plurality of cross beams arranged between the side members of said frame, a plurality of rows of burner plates arranged between said beams and removably mounted on the lower flanges thereof, each alternate row of said plates having fuel burners and air inlet apertures therein, and the other rows being provided with air inlet apertures only. 115

7. In an igniter car comprising a rectangular wheeled main frame, and a plurality of 120

cross beams arranged between the side members of said frame, a plurality of rows of burner plates arranged between said beams and removably mounted on the lower flanges thereof, each alternate row of said plates having fuel burners and air inlet apertures therein, and the other rows being provided with air inlet apertures only, and flanges on

said burner plates adapted to underlie the lower flanges of said cross beams so as to protect them from the intense heat generated in said igniter.

In testimony whereof we have hereunto set our hands.

THOMAS J. DAVIS.
JOHN W. FORSYTHE.
